MEANS AND METHOD FOR EXTINGUISHING
AN ARC SPOTCharles G. Smith, Medford, Mass., assignor to
Raytheon Manufacturing Company, Newton,
Mass., a corporation of Delaware

Application December 11, 1941, Serial No. 422,562

9 Claims. (Cl. 250—27.5)

This invention relates to means and method for extinguishing an arc spot, particularly on a pool type cathode of an electrical space discharge tube.

Heretofore attempts to control currents of relatively high values by extinguishing the flow of current in an arc discharge tube have been unsuccessful because of the large amount of power necessary and the unreliability of the resultant operation. I believe that the failure of such prior attempts has been due largely to the fact that a tenable theory of operation of the arc spot had not been developed, and consequently the proposed methods of current stoppage control were not properly adapted to the phenomena existent in the arc discharge.

The primary object of this invention is to devise a reliable means for extinguishing an arc spot, and thus control the flow of current in an arc discharge tube.

This and other objects of my invention will be best understood from the following description of an exemplification thereof, reference being had to the accompanying drawing, wherein:

Fig. 1 is a diagram illustrating certain principles of the theory of operation of my invention; and

Fig. 2 is a diagrammatic representation of a system with which my invention may be practised.

In accordance with my invention I have been able to overcome the previous difficulties, and have devised means whereby relatively large arc currents have been reliably extinguished by the use of surprisingly small amounts of controlled power and in remarkably short intervals of time. I believe that these results are due to my new analysis of the arc spot conditions and to my development of a tenable theory of the operation of such arc spots.

In accordance with my present understanding, the theory of the operating mechanisms of an arc spot is substantially as follows. In Fig. 1 is represented a small cross-section through the surface of a mercury pool cathode on which an arc spot extending between the two vertical broken lines may be considered as in operation. Immediately adjacent the surface of the cathode above the arc spot is the cathode dark space which is populated mainly by positive ions. The thickness of this space is ordinarily considered as being of the order of 10^{-4} centimeters. Beyond that space is located a plasma of electrons and ions in substantially equal numbers. The potential fall through the cathode dark space is

termed the cathode drop, and may be of the order of nine volts and probably less. The temperature of the electrons in the plasma may be of the order of $30,000^{\circ}$ K., which means that the electrons in the plasma are in thermal agitation and are travelling at various speeds in all directions. The average speed of the electrons expressed in equivalent volts may be of the order of about four volts. Since this is an average value, a great many electrons in the plasma will have a component of velocity toward the cathode in excess of the cathode drop. These electrons, therefore, have sufficient velocity to overcome the cathode drop, whereby they pass through the cathode dark space and fall upon the cathode surface, and deliver considerable energy thereto. This energy consists of the kinetic energy of the electrons, and also the condensation energy thereof. The body of the cathode pool, including the surface layer, may be considered as consisting of a lattice of relatively heavy atoms within which is located an atmosphere of relatively free conduction electrons. Although the lattice of a liquid may not have as orderly an arrangement as in the case of a solid, particularly a crystal, yet for the purposes of this analysis the arrangement of the atoms in the mercury has the properties of an atomic lattice. The probability of energy transfer between the colliding electrons and the atomic lattice is small due to the disparity between the mass of the electron and the mass of the component parts of the atomic lattice. However, the colliding electrons have a high probability of transfer of energy to the relatively free conduction electrons within the atomic lattice of the surface of the mercury pool. As a result of this transfer of energy, the temperature of the electrons in a very thin layer at the surface of the mercury pool is raised to a relatively high value which may be of the order of 4500° K. This electronic temperature is, of course, not in equilibrium with the temperature of the atomic lattice which is probably of the order of about 200° C. However, the rate of energy transferred to the electronic atmosphere by the impinging electrons is sufficiently high to maintain this temperature differential between the electronic atmosphere and the atomic lattice in spite of energy transferred to the atomic lattice from the electronic atmosphere.

The relatively high temperature of the electronic atmosphere within the surface of the mercury pool gives rise to a large emission which may be considered in the nature of thermionic emission. In order to differentiate between the

ordinary type of thermionic emission, in which the electronic atmosphere and the atomic lattice are in equilibrium, I may refer to this new type of emission as β -thermionic emission. When the current carried by an arc is ordinarily measured, the quantity observed is the difference between the rate at which the electrons leave the cathode surface to enter the space above it and the rate at which electrons return to the cathode surface from the plasma, as described above. In Fig. 1 the β -thermionic emission current L is represented by the solid arrows, leaving the surface of the mercury pool, the returning electron current I is represented by the dotted arrows re-entering the surface of the cathode, and the difference electronic current D is represented by the solid arrow in the body of the mercury pool.

In absence of some means to maintain the relatively high temperature of the electronic atmosphere at the surface of the mercury pool, the heat would be rapidly conducted away from the surface layer by the conduction electrons, and transferred to lower regions of the mercury pool. It is well known that if a temperature gradient exists in a conducting body and an electronic current is passed through that body along the temperature gradient, there is a transfer of heat due to the current. This is known as the Thomson effect. The direction in which this transfer takes place may be different in different conducting materials. However, in the case of mercury under the conditions here existing, the transfer of heat is in the direction in which the electronic current flows. If we look at Fig. 1 we see that the electronic current in the body of the mercury pool is the difference current D which is in a direction to transfer heat to the surface of the mercury pool from the regions below said surface. This transfer under the conditions involved is sufficiently great so that the heat transfer by conduction through the conduction electrons is compensated for by the Thomson effect. I believe that the elevated temperature of the conduction electrons is confined to a thin surface layer on the mercury having the thickness of the order of a few hundred atomic diameters, approximately 10^{-5} centimeters.

We can derive some valuable information by equating the energy input to the cathode surface by the impinging electrons and the energy loss therefrom by the evaporating or β -thermionic emission electrons. First we can formulate the equation for the return electronic current:

$$I = Ne \sqrt{\frac{kT}{2\pi m}} e^{-\frac{eC}{kT}} \quad (\text{Equation 1})$$

in which:

N =number of electrons per c. c. in the plasma immediately adjacent the anode side of the cathode dark space;

$e=1.6 \times 10^{-19}$, this being the electronic charge in coulombs;

k =Boltzman's gas constant per molecule;

T =electronic temperature in the plasma;

$e=2.718$; and

$c=1.6 \times 10^{-12} \times C$, where C is the cathode drop in volts.

We can then give the energy balance equation as follows:

$$\frac{3}{2} \frac{I}{e} kT + \theta I \times 10^7 = \phi L \times 10^7 + \frac{3}{2} \frac{L}{e} k\theta \quad (\text{Equation 2})$$

in which:

θ =temperature of the conduction electrons in the surface layer of the liquid cathodes; and
 ϕ =work function of mercury.

In Equation 2 I have neglected the energy transfer due to positive ions. However, this is such a small factor that it does not substantially affect our present considerations. We also have determined that the β -thermionic emission current is equal to the sum of the difference current and the return current, namely

$$L = D + I \quad (\text{Equation 3})$$

From a consideration of the energy equation as well as from various other factors, I have determined that the current I may be of the order of 2000 or 3000 amperes per square centimeter under certain conditions, while the current D is of the order of 3000 or 4000 amperes per square centimeter. Thus L under these conditions would be of the order of 5000 to 7000 amperes.

Having established the above relationships, I conceived that if at any time conditions were changed so that the temperature of the conduction electrons in the arc spot was reduced substantially, the β -thermionic emission would be decreased to such an extent as to be incapable of maintaining the arc spot. In accordance with

my invention I successfully accomplished the extinguishment of the arc spot by suddenly increasing the difference current D in an interval of time sufficiently short so that the state of excitation of the plasma remained substantially constant. From Equations 2 and 3 we see that an increase in D under these conditions would produce a direct decrease in I , so that the rate at which energy is supplied to the arc spot is decreased. This in turn produces a decrease in the temperature of the conduction electrons in the surface of the cathode, and a consequent decrease in the β -thermionic emission. Such decrease produces, of course, a higher cathode voltage drop, which in turn tends to still further decrease the ability of electrons to return to the cathode, and thus still

further decreases I . This cumulative effect in an interval of time, which may be of the order of 10^{-7} of a second is sufficient to extinguish the arc spot. Depending upon the rate at which equilibrium conditions can establish themselves

in the plasma, this interval of time may be considerably longer or shorter. The criterion which should exist in each case is that the rate of change of the current D should be greater than that at which equilibrium conditions can estab-

lish themselves in the plasma. Another manner in which extinguishment may occur is to interrupt or reverse the current D which causes the Thomson effect to maintain the high temperature gradient at the surface of the cathode. If

the current D is interrupted or reversed likewise for a very short period of time of the above order of magnitude, heat is conducted from the surface layer to the conduction electrons below it at such a rapid rate as to lower the temperature of the conduction electrons to such an extent that the thermionic emission and consequently the arc spot are extinguished.

One arrangement whereby either or both of the above methods of extinguishing the arc spot may be carried out is illustrated in Fig. 2. In this figure, 1 represents an electrical discharge tube of the type having an arc cathode 2, preferably of the mercury pool type, an anode 3, and an igniting electrode 4. The igniting electrode 4 is preferably of the electrostatic type consisting of

70
75

an insulator separated from the surface of the mercury pool by means of an insulating layer thereon in contact with said surface. Current is supplied to the tube 1 from a pair of terminals 5-6 which, for example, are adapted to be connected to a suitable source of direct current. This source of current is connected through a load 7 in series with the tube 1 so that the current in the load 7 may be controlled. High frequency choke coils 8-9 may be included in the circuit for purposes to be described below. In order to supply igniting impulses to the electrode 4, an igniting transformer 10 may be provided having a secondary winding 11 connected between the igniting electrode 4 and the cathode 2. The transformer 10 may also be provided with a primary winding 12 supplied with impulses of igniting current from a condenser 13 adapted to be charged from a suitable source of current, such as a battery 14, connected in series with a resistance 15 across said condenser. A switch 16 is adapted to connect the condenser 13 when charged to the primary winding 12 in order to supply an igniting impulse to the igniting electrode 4. When such an igniting impulse is supplied and an arc spot is started on the cathode 2, current will flow through the tube 1 and the load 7.

In order to extinguish the arc spot on the cathode 2, an auxiliary circuit incorporating the principles of my invention as outlined above may be utilized. The energy for the rapid change of the current through the tube may be supplied from a condenser 17 which is adapted to be charged with a predetermined polarity from a suitable source of current, such as a battery 18, connected in series with a resistance 19 across said condenser. In order that the polarity to which the condenser 17 is to be charged may be reversed if desired, a reversing switch 17' is interposed between the battery 18 and the condenser 17. The charged condenser 17 may be connected through a switch 20 to a coil 21. In series with this circuit may be included a resistance 21' wherever it is desired that the discharge from the condenser 17 shall be damped or non-oscillatory. In this case the resistance 21' is of sufficient magnitude to produce the desired damping. Inductively coupled to the coil 21 is a coil 22 connected in series with a condenser 23 between the cathode 2 and the anode 3. Here likewise in series with this circuit may be included a small resistance 24.

In the preferred mode of operation of the system shown in Fig. 2, the condenser 17 is charged to polarities as indicated, so that upon closure of the switch 20, a discharge current flows in the direction of the arrow in coil 21 and an induced current flows in the direction of the corresponding arrow in coil 22. It will be seen that this induced current is in a direction to tend to cause the current through the tube 1 to increase. This current impulse is of a very sharply rising characteristic so as to tend to increase the current through the tube 1 within the necessary short time interval, as described above, in order to cause the arc spot to be extinguished. In a particular instance I have used the following values for the elements of this extinguishing circuit. The condenser 17 was 2×10^{-8} farads charged to about 500 volts, the coils 21 and 22 were each a single turn of copper four inches in diameter, the resistance 21' was five ohms, the resistance 24 was substantially zero, and the condenser 23 was 5×10^{-8} farads. Under these conditions currents

of about 20 amperes could be readily extinguished in the tube 1 within the short time interval as described above. I believe that the peak increase in current during this pulse should be of the order of magnitude of that of the preceding arc current or somewhat less. The chokes 8 and 9 previously referred to are inserted for the purpose of preventing the sharply rising pulse of current supplied from the condenser 17 from bypassing the tube 1 through the load 7.

Upon reversal of the switch 17', it will be seen that the condenser 17 will be charged to the opposite potential, and upon closure of the switch 20 a pulse of current tending to reduce and reverse the current through the tube 1 will be induced in the coil 22. I have found that with the same constants as previously used, currents of the order of twenty amperes can likewise be readily extinguished in the tube 1 in the short time interval described above. I have found, however, that extinguishing an arc spot by reduction or reversal of the current ordinarily requires a greater amount of energy stored in the condenser 17 than in the case of extinguishment by a sudden increase in the current flowing through the tube.

For most purposes I prefer to have the condenser 23 of substantially greater value than that described in the particular example which I have given. In connection with the extinguishing circuit in the particular embodiment which I have shown, the condenser 23 serves to prevent the direct current from short-circuiting across the tube 1. However, by making this condenser of substantial size, the reliability with which the starting electrode initiates an arc spot is greatly increased, as more fully described and claimed in the copending application of Wilcox P. Overbeck, Serial No. 271,679, filed May 4, 1939, for an improvement in Arc tube systems. We see, therefore, that the circuit connected between the cathode 2 and the anode 3 may be made to serve the double function of facilitating the initiation of the arc spot, and also serving to extinguish the arc spot.

Of course it is to be understood that this invention is not limited to the particular details of construction, magnitude, and the like, as described above, as many equivalents will suggest themselves to those skilled in the art. For example, the principles of my invention can be applied to polyphase rectifier tubes or to any type of tube in which an arc spot may be extinguished for purposes of controlling a current. It is believed that the principles which I have enunciated are so broadly new that an extremely wide and varied number of utilizations thereof will suggest themselves to those skilled in the art. It is accordingly desired that the appended claims be given a broad interpretation commensurate with the scope of the invention within the art.

What is claimed is:

1. The method of extinguishing an arc spot on a localized arc spot type of cathode which comprises suddenly changing the current flow to said cathode, said change being carried out at a rate so rapid that said arc spot is extinguished in a period of time of the order of 10^{-7} second or less after the initiation of said change.
2. The method of extinguishing an arc spot on a localized arc spot type of cathode which comprises increasing the flow of current to said arc spot at such a rapid rate as to cause said spot to be extinguished, said change being carried out at a rate so rapid that said arc spot is extin-

guished in a period of time of the order of 10^{-7} second or less after the initiation of said change.

3. The method of extinguishing an arc spot on a localized arc spot type of cathode which comprises reducing the flow of current to said arc spot at such a rapid rate as to cause said spot to be extinguished, said change being carried out at a rate so rapid that said arc spot is extinguished in a period of time of the order of 10^{-7} second or less after the initiation of said change.

4. In combination with a discharge tube of the type comprising a localized arc spot type cathode and a cooperating electrode, means for establishing and maintaining an arc spot on said cathode, and means for suddenly changing the flow of current to said arc spot at a rate so rapid that said arc spot is extinguished in a period of time of the order of 10^{-7} second or less after the initiation of said change.

5. In combination with a discharge tube of the type comprising a localized arc spot type cathode and a cooperating electrode, means for establishing and maintaining an arc spot on said cathode, and means for suddenly increasing the flow of current to said arc spot at a rate so rapid that said arc spot is extinguished in a period of time of the order of 10^{-7} second or less after the initiation of said change.

6. In combination with a discharge tube of the type comprising a localized arc spot type cathode and a cooperating electrode, means for establishing and maintaining an arc spot on said cathode, electrical energy storage reservoir means, and means for connecting said reservoir means to feed energy between said cathode and cooperating electrode in a direction to increase the flow of current to said arc spot, the impedance of that portion of the system leading from said reservoir means to said cathode and cooperating electrode being sufficiently small to current surges and said reservoir means being of sufficient size to cause said change in current flow to occur at a sufficiently great rate to extinguish said arc spot in a period of time of the order of 10^{-7} second or less after the initiation of said change.

7. In combination with a discharge tube of the type comprising a localized arc spot type cathode and a cooperating electrode, means for establish-

ing and maintaining an arc spot on said cathode, electrical energy storage reservoir means, and means for connecting said reservoir means to feed energy between said cathode and cooperating electrode in a direction to reduce the flow of current to said arc spot, the impedance of that portion of the system leading from said reservoir means to said cathode and cooperating electrode being sufficiently small to current surges and said reservoir means being of sufficient size to cause said change in current flow to occur at a sufficiently great rate to extinguish said arc spot in a period of time of the order of 10^{-7} second or less after the initiation of said change.

5 8. In combination with a discharge tube of the type comprising a localized arc spot type cathode and a cooperating electrode, means for establishing and maintaining an arc spot on said cathode, condenser means, and means for connecting said condenser means to feed energy between said cathode and cooperating electrode in a direction to increase the flow of current to said arc spot, the impedance of that portion of the system leading from said condenser means to said cathode and cooperating electrode being sufficiently small to current surges and said condenser means being of sufficient size to cause said change in current flow to occur at a sufficiently great rate to extinguish said arc spot in a period of time of the order of 10^{-7} second or less after the initiation of said change.

10 9. In combination with a discharge tube of the type comprising a localized arc spot type cathode and a cooperating electrode, means for establishing and maintaining an arc spot on said cathode, condenser means, and means for connecting said condenser means to feed energy between said cathode and cooperating electrode in a direction to reduce the flow of current to said arc spot, the impedance of that portion of the system leading from said condenser means to said cathode and cooperating electrode being sufficiently small to current surges and said condenser means being of sufficient size to cause said change in current flow to occur at a sufficiently great rate to extinguish said arc spot in a period of time of the order of 10^{-7} second or less after the initiation of said change.
